UNITED STATES PATENT OFFICE

2,527,194

FOLDING JAW ASSEMBLY FOR ROTARY
SHEET FOLDERS

Joseph E. Meyer, Westerly, R. I., assignor to C. B. Cottrell & Sons Company, Westerly, R. I., a corporation of Delaware

Application February 7, 1947, Serial No. 727,202

9 Claims. (Cl. 270—71)

1

My invention is directed to a novel, simple and effective folding jaw assembly for rotary sheet folders, in which one of the folding jaws is fixed to the folding cylinder and the other coacting folding jaw is journaled in the cylinder to rock to and from its sheet gripping position.

One object of my invention is to provide the rocking folding jaw with a plurality of aligned gripping blades arranged in groups, if so desired, each gripping blade being composed of a single thickness of comparatively thin resilient sheet material, as sheet metal, a common means being provided for removably clamping all of the gripping blades to the rocking jaw, thereby eliminating the necessity of separate fastening devices for each gripping blade and also eliminating the necessity of perforating the blades to permit the individual fastening devices to pass therethrough.

Another object is to provide a rocking folding jaw of very light construction by providing a thin reinforced intermediate portion and short stud shafts projecting from the ends of said intermediate portion to journal the rocking jaw in the cylinder.

Another object is to provide means whereby the gripping blades may be accurately positioned both laterally and endwise on the rocking folding jaw.

Another object is to provide means for initially tensioning the gripping blades whereby the folding jaw assembly will successfully handle thin or thick products and whereby side-by-side products of different thicknesses may also be handled without requiring additional adjustment for tension of the said gripping blades.

A practical embodiment of my invention is represented in the accompanying drawings, in which

Fig. 1 represents a detail side elevation of a folding cylinder showing the outside view of one of the folding jaw assemblies in its normal position;

Fig. 2 represents a longitudinal section taken in the plane of the line II—II of Fig. 1;

Fig. 3 represents a detail transverse section taken in the plane of the line III—III of Fig. 1;

Fig. 4 represents a detail transverse section taken in the plane of the line IV—IV of Fig. 1;

Fig. 5 represents a detail transverse section taken in the plane of the line V—V of Fig. 1;

Fig. 6 represents a detail section like Fig. 4 of the folding jaw assembly for gripping a single sheet;

Fig. 7 represents a similar section of the folding jaw assembly for gripping a plurality of sheets;

Fig. 8 represents a detail plan view, on an enlarged scale, of the rocking folding jaw;

Fig. 9 represents a detail front view of the same;

2

Fig. 10 represents an end view of the rocking folding jaw; and

Fig. 11 represents a vertical cross section in the plane of the line XI—XI of Fig. 9.

5 The folding jaw cylinder 1 has its shaft 2 rotatably mounted in suitable side frames 3. This cylinder may be provided with the usual longitudinal recess 4 opening through the periphery of the cylinder.

10 The fixed folding jaw 5 which extends substantially the length of the cylinder 1 may be secured as by screws 6 in position to partially close the mouth of the recess 4. The gripping face of the fixed jaw 5 is shown as radially disposed with respect to the cylinder shaft 2.

A filling piece 7 extends along the mouth of the recess 4 opposite the fixed jaw 5 and may be secured by screws 8 to the cylinder 1.

The rocking folding jaw which coacts with 20 the fixed folding jaw 5 to fold the sheets comprises a thin wide reinforced intermediate portion 9 from which project short end stud shafts 10 and 11 journaled in suitable anti-friction bearings 12 and 13 at the ends of the cylinder 1.

25 This elongated wide portion 9 of the rocking folding jaw is provided with a flat portion 14 for removably seating the inner ends of aligned resilient gripping blades 15 of sheet material preferably arranged in spaced groups of three blades each.

30 This flat portion 14 terminates in an uprising flange 16 against which the inner ends of the gripping blades 15 abut, to endwise position the said blades. The outer ends of these blades have gripping faces for coaction with the gripping face of the fixed jaw 5. An uprising flange 17 extends along the outer edge of the elongated portion 9 of the rocking jaw in position to bear against the outer ends of the gripping blades 15 to initially tension the blades when the blades are clamped to the said elongated portion 9.

35 Narrow and wide spacing lugs 18 and 18* project from the flange 17, the narrow lugs serving to space the blades of each group apart and the wide lugs 18* serving to space the groups of

40 blades apart along the jaw. These lugs 18 and 18* serve to laterally space the gripping blades and coact with the flange 17 to accurately position the blades both endwise and laterally.

The common means for clamping the spaced 45 gripping blades to the rocking jaw includes a retaining plate 19 extending along the elongated portion 9 of the jaw over the inner ends of the gripping blades, screws 20 being provided for connecting the plate 19 and elongated portion 9.

50 These screws 20 pass between the groups of blades, thereby permitting the blades to be made imperforate and much stronger than when the blades are perforated, as is usual heretofore in the art, to receive fastening screws therethrough.

55 This imperforate construction of the gripping

blades also permits either end of the blade to be clamped to the rocking folding jaw.

When the screws are tightened to clamp the gripping blades to the rocking folding jaw the outer ends of these blades will be slightly deflected and thereby placed under initial tension by the pressure of the blades 15 against the flange 17.

The means for operating the rocking folding jaw comprises the following elements. Rock arms 21 and 22 are secured to the ends of the stud shafts 10 and 11, which rock arms are yieldingly held at the limit of their closing movement by the usual spring devices 23 and 24. One of these arms, in the present instance the arm 22, is provided with a cam roller 25 arranged to be opened at the proper time by the usual fixed cam 26 (shown in dotted lines in Fig. 3) projecting inwardly from its adjacent side frame 3. Projections 27 and 28 on the arms 21 and 22 engage the stops 29 and 30 on the blocks 31 and 32 carried by the cylinder 1, for limiting the closing movement of the rocking folding jaw.

From the above description it will be seen that when the screws 20 are tightened to cause the retaining plate 19 to clamp the inner ends of the gripping blades 15 to the elongated wide portion 9 of the rocking folding jaw the outer ends of these blades will be slightly deflected and thereby placed under the required initial tension by the action of the flange 17 to properly grip products of different thicknesses without further adjustment of the gripping blades.

It will also be seen that the tension of the gripping blades does not have to be individually adjusted when handling side-by-side products of different thicknesses as the tension of the gripping blades will be automatically increased as the thickness of the product increases.

It will also be seen that by the construction herein set forth the rocking folding jaw may be made extremely light and strong and at the same time provide a wide bearing for the row of aligned resilient gripping blades. Also, by this novel construction each gripping blade may be made of a single piece of sheet material thereby eliminating the necessity of providing a laminated structure.

It is evident that various changes may be resorted to in the construction, form and arrangement of the several parts without departing from the spirit and scope of my invention, and hence I do not intend to be limited to the particular embodiment herein shown and described, but what I claim is:

1. In a rotary sheet folder, a cylinder and a folding jaw assembly carried thereby comprising a fixed jaw, a coacting rocking jaw having a thin wide reinforced elongated intermediate portion and stud shafts projecting from its ends and journaled in the cylinder, aligned imperforate resilient gripping blades and a common means for removably clamping all of the blades to the said intermediate portion of the rocking jaw.

2. In a rotary sheet folder, a cylinder and a folding jaw assembly carried thereby comprising a fixed jaw, a coacting rocking jaw having a thin wide reinforced elongated intermediate portion and stud shafts projecting from its ends and journaled in the cylinder, and spaced groups of aligned resilient gripping blades and a common means for removably clamping all of the blades to the said intermediate portion of the jaw.

3. In a rotary sheet folder, a cylinder and a folding jaw assembly carried thereby comprising a fixed jaw, a coacting rocking jaw having a thin 75 portion having uprising flanges along its inner

wide reinforced elongated intermediate portion, stud shafts projecting therefrom and aligned resilient gripping blades removably clamped thereto, said intermediate portion being provided along its inner edge with means for positioning the blades endwise and along its outer edge with means for spacing the blades laterally, said wide elongated portion also being provided with means for placing the outer ends of the resilient blades under initial tension.

4. In a rotary sheet folder, a cylinder and a folding jaw assembly carried thereby comprising a fixed jaw, a coacting rocking jaw, and aligned imperforate resilient gripping blades removably clamped to the rocking jaw, said rocking jaw having a wide elongated portion provided along its inner edge with an uprising flange for positioning the blades endwise and with an uprising flange along its outer edge for placing the outer ends of the resilient blades under initial tension, said last named flange having uprising lugs for spacing the blades laterally.

5. In a rotary sheet folder, a cylinder and a folding jaw assembly carried thereby comprising a fixed jaw, a coacting rocking jaw having a wide elongated portion, and aligned groups of imperforate resilient gripping blades removably clamped thereto, said wide elongated portion being provided along its inner edge with an uprising flange for positioning the blades endwise, and with an uprising flange along its outer edge for normally placing the outer ends of the resilient blades under initial tension, said last named flange having uprising lugs for spacing the blades laterally.

6. In a rotary sheet folder, a cylinder and a folding jaw assembly carried thereby comprising a fixed jaw, a coacting rocking jaw, spaced aligned imperforate resilient gripping blades, and means for removably clamping the blades to the rocking jaw including a retaining plate extending along the rocking jaw over the inner ends of all of the blades, and fastening devices connecting the retaining plate to the rocking jaw through the spaces between predetermined blades.

7. In a rotary sheet folder, a cylinder and a folding jaw assembly carried thereby comprising a fixed jaw, a coacting rocking jaw, spaced aligned groups of imperforate gripping blades, each blade consisting of a single thickness of thin resilient sheet material, and means for removably clamping the blades to the rocking jaw including a retaining plate extending along the rocking jaw over the inner ends of all of the blades, and fastening devices connecting the retaining plate to the rocking jaw through the spaces between predetermined groups of blades.

8. In a rotary sheet folder, a cylinder and a folding jaw assembly carried thereby comprising a fixed jaw, a coacting rocking jaw having a wide elongated portion provided with end stud shafts journaled in the cylinder, spaced aligned imperforate gripping blades, each blade being composed of a single thickness of thin resilient sheet material, and means for removably clamping the blades to the said wide elongated portion including a retaining plate extending along the said wide elongated portion over the inner ends of all of the blades, and screws connecting the retaining plate to the said wide elongated portion through the spaces between predetermined blades.

9. In a rotary sheet folder, a cylinder and a folding jaw assembly carried thereby comprising a fixed jaw, a coacting jaw comprising end stud shafts and a thin wide reinforced intermediate portion having uprising flanges along its inner

and outer edges, a flat portion along the inner flange and narrow and wide lugs uprising from the outer flanges, aligned groups of imperforate gripping blades seated at their inner ends on said flat portion and spaced individually by said narrow lugs and as groups by said wide lugs, each blade being composed of a single thickness of thin resilient sheet material and a common means for removably clamping the gripping blades to the intermediate portion under initial tension. 10
